VENTILATED BLACKBOARD INSTALLATION

Filed Sept. 17, 1928

INVENTOR:
John F. Johnson.

By: Charles H. Kelly
Att.

UNITED STATES PATENT OFFICE

JOHN F. JOHNSON, OF CHICAGO HEIGHTS, ILLINOIS, ASSIGNOR TO WEBER COSTELLO COMPANY, OF CHICAGO HEIGHTS, ILLINOIS, A CORPORATION OF ILLINOIS

VENTILATED BLACKBOARD INSTALLATION

Application filed September 17, 1928. Serial No. 306,530.

This invention relates to blackboards and particularly to the installation of the same, whereby the boards may be ventilated to prevent sweating, or the collection or condensation of moisture on the blackboards and to keep the same dry, especially in humid climates, so that the boards may be properly written on with blackboard crayon and readily and thoroughly cleaned by the ordinary blackboard erasers.

I have found that all blackboards sweat and become damp in humid climates, necessitating the replacement of the boards at much expense and because of the dampness chalk marks are very indistinct and cannot be properly made and completely erased.

I have overcome the above objections by ventilating the blackboard in such a manner as to permit circulation of air behind the board so that the same will remain dry even in very humid climates, and as a result the chalk marks may be properly made and erased.

An object of the invention is to provide a blackboard installation whereby the blackboard will not sweat.

Another object of the invention is to provide a blackboard which will remain dry so that chalk marks may be properly made so that they are easily removed and completely erased.

A further object is to provide a blackboard which may be used in any climate without sweating, and which remains dry under all circumstances, and one which may be economically installed.

When chalk or crayon marks are made on a damp or wet blackboard, the nature of the ingredients of the crayons is such as to cause the particles left on the board, from the chalk or crayon, to become cemented to the blackboard with the result that a scum or film forms over the surface. This renders the writing surface valueless, and must be removed to restore the writing surface. By ventilating the blackboard, as is the object of this invention, sweating and the condensation or collection of moisture and the formation of chalk scum is overcome and this objection is eliminated.

The above, other and further objects will be apparent from the following description, the accompanying drawings and the appended claims:

According to the invention, a blackboard is attached to a wall with furring strips, so that the board stands outwardly from the surface of the wall, the board being fastened to the furring strips by plastic material, such as cement, or otherwise.

The blackboard may also be fastened to a backing of wallboard, wood or other material which is superimposed upon the furring strips.

One form of the invention is illustrated in the accompanying drawings, and the views thereof are as follows:

Figure 1 is a fragmental perspective view of a wall showing a blackboard secured thereto, in accordance with this invention.

Figure 2 is an enlarged vertical section through Figure 1.

Figure 3 is an enlarged horizontal section.

There is shown in Figure 1 a portion of a wall 1 having the usual baseboard 2 along the floor. The blackboard 3 is secured to the wall 1 in the following manner:

Horizontal headers or grounds 4 and 5 are secured to the backing 6 of the wall so as to lie flush with the surface of the finish 7. Plaster on the wall behind the blackboard is not essential as the horizontal leaders of grounds 4 and 5 can be put on the studding, lath, brick or such other material as may be used for the wall. Vertical or horizontal furring strips 8 are attached to the headers 4 and 5 at spaced intervals. Plastic material such as cement 9 (or such other material for fastening as may be used) is applied to the several furring strips, and the blackboard sections 3 are then placed against the plastic material 9 so as to cause the blackboard sections to adhere and thus be held firmly in position.

The blackboard sections 3, when the blackboard is a long one, may have the adjacent ends of several sections covered by an overlap or connecting strip 10 to improve the appearance of the board. The blackboard may also be joined by what is known as a "butt joint." 100

A frame comprising vertical members 11, top horizontal members 12 and lower horizontal members 13 may be constructed so as to provide a finish for the blackboard but not so as to close the air spaces behind the board.

5 A cork insert 14 may be affixed along the upper part of the board for uses well understood.

The spaces formed between the furring strips 8 are open at the top and bottom so as to permit free circulation of air behind the board. When horizontal furring strips are used, the openings will be the ends of the board. Circulation of air through these 15 spaces keeps the board dry, thus preventing sweating and also preventing formation of chalk scum thereby preventing the chalk marks from becoming indistinct.

While I have described more or less precisely the details of construction of my invention, yet I do not wish to be understood as limiting myself thereto, as I am aware that changes may be made in the arrangement and proportion of parts and equivalents may 25 be substituted, all without departing from the spirit and scope of my invention.

I claim as my invention:

1. In combination in an apparatus for supporting a blackboard of the wall type solely 30 by a wall in such a manner as to preclude the deposit of sweat on the board as a result of its proximity to the wall and to thus preclude the formation of chalk scum of the character described thereon, strips for spacing the 35 board from the wall and additional supporting means for the board in said spacing arranged to define substantially vertical passageways to allow a natural draft of atmospheric air to circulate through each of the 40 passageways.

2. The combination with a blackboard of the wall type of means for supporting the board on a wall in such a manner as to preclude the deposit of sweat on the board as a 45 result of its proximity to the wall, including spacers between the board and the wall arranged to define substantially a vertical passageway for causing a natural draft of atmospheric air to circulate between the wall and the board.

50 In testimony whereof I have hereunto subscribed my name at Chicago Heights, Cook County, Illinois.

JOHN F. JOHNSON.
